Leonce Picot of Hoboken No. 9.

Assigns all his right to

The Rubber Clothing Co. of New York.

Letters Patent No. 2482. Dated Oct. 3, 1866.

Design for a Childs Long Comb.

The structure referred to in the Letters Patent, and making part of the same.

To all whom it may concern:

Be it known that Leonce Picot, of Hoboken in the County of Hudson and State of New Jersey, have invented or produced a new and original Design for ornamenting Children's Long Combs; and I do hereby declare the following to be a full, clear and exact description of the same, reference being had to the accompanying drawing.

The Design as there represented consists of a chain of the form shown, and of suitable material which is extended around the upper part of the face of comb above the teeth. The chain is looped up at intervals by means of pins or studs which have beads of different colors to match or suit the chains with which they are used, secured on their outer ends. The pins are riveted to the comb and support the chain. The chain thus looped up has a

wavy or scalloped configuration, and the general direction is parallel to the top edge of the comb. Now I am describing my invention what I claim and desire to secure by Letters Patent is: The design for ornamenting children's long combs as herein shown and described.

In testimony whereof I have signed my name to this specification before two subscribing witnesses. Witnesses
